Attorney

UNITED STATES PATENT OFFICE.

FRED C. WERBER, OF WILKES-BARRE, PENNSYLVANIA.

SADDLE.

Application filed December 13, 1926. Serial No. 154,576.

This invention relates generally to thread spinning and twisting machines and has particular reference to a saddle construction for supporting the thread delivery bobbin 5 of the spinning and twisting unit.

The primary object of the invention is to greatly improve and simplify that type of saddle shown and described in my Patent No. 1,569,831. To this end there is provided a saddle that is constructed for rapid disposition upon or removal from the spindle and that under usual working conditions has contact with the spindle practically at but a single point for obviously reducing friction between the saddle and spindle. Furthermore the spindle is so constructed as to have a further point of contact with the spindle normally out of engagement with the spindle during high speeds thereof. This additional point of contact is for the purpose of preventing the swinging of the saddle upon the spindle prior to the time that said spindle reaches a high degree of rotation.

The invention further aims to provide a saddle wherein the spindle contacting member is of such formation as to engage within a circumferential channel in the spindle for positively preventing any longitudinal movement of the saddle upon the spindle after it has been properly disposed thereon.

A still further object resides in the provision of a saddle that is so constructed as to permit the operator of the machine to readily grasp the unit spindle for the purpose of stopping the same which is necessary in the rethreading of the unit.

A final salient object is to provide a bobbin supporting saddle for spinning and twisting units wherein means is provided for frictionally engaging the thread delivery bobbin for checking the rotation of the same during the operation of the unit.

Other objects will become apparent as the nature of the invention is better understood, the same comprising the novel form, combination, and arrangement of parts herein-after more fully described, shown in the accompanying drawing and claimed.

In the drawing wherein like reference characters indicate corresponding parts throughout the several views:

Figure 1 is a fragmentary side-elevation of a spinning and twisting unit of the general construction shown and described in

my previously mentioned patent, the same being disclosed as equipped with a bobbin supporting saddle constructed in accordance with the present invention and upon which is disposed a thread delivery bobbin.

Figure 2 is a section through the saddle upon the spindle, the full lines disclosing the normal position of the saddle upon the spindle when a thread delivery bobbin is associated therewith, while the dotted lines disclose the position of the saddle with respect to the spindle during the application or removal of the saddle.

Figure 3 is a top plan view of the saddle upon the spindle.

Figure 4 is a vertical section taken substantially upon the line 4—4 of Figure 1.

Figure 5 is an enlarged detail vertical section taken substantially upon the line 5—5 of the same Figure for more clearly disclosing the single point of suspension of the saddle upon the spindle.

Figure 6 is a transverse section taken substantially upon the line 6—6 of Figure 4 disclosing the second point of suspension between the saddle and spindle, which second point of suspension is as previously stated normally out of contact with the spindle but that will engage the spindle during low speeds thereof to limit the wobbling of the saddle upon the spindle at such low speeds.

Figures 7 and 8 are perspectives of fiber plates carried by the two points of suspension of the saddle, and

Figure 9 is a view mainly in front elevation of a modified form of saddle constructed for the purpose of permitting the suspension of two delivery bobbins upon the spindle, the bobbin receiving pins being disclosed in cross section.

The present saddle construction is of sheet metal formation consisting of a single strip of metal so bent as to provide a horizontal top wall 5, and an elongated depending rear wall 6, the inner portion of which is at 100 direct right angles to the top wall, while the remainder thereof is bent diagonally forwardly as clearly indicated in Figures 1 and 2.

The forward end of the top wall 5 of the saddle is bent directly downwardly as at 7, and upon the rear face thereof is disposed a fibre plate 8. The ends of the portion 7 of the saddle are bent inwardly as at 9—9' over the forward face of the fiber plate so

as to firmly secure the same to said saddle. The lower edge of this fiber plate extends below the edge of the saddle portion 7, and is formed at said lower edge with a relatively U-shaped notch 9, the edge of which is rounded as disclosed in Figure 2.

This notch of said fibre plate is for the purpose of supporting the plate within a circumferential groove α , Figure 2, adjacent to the outer end of the spindle A of a spinning and twisting unit as shown and described in my before mentioned patent. The transverse area of this notch is slightly greater than the transverse size of the spindle at the groove α , but less than the transverse size of the spindle proper or the un-grooved portion thereof so that the fiber plate and saddle will be prevented from longitudinal movement upon the spindle after the saddle has been properly disposed thereon.

Upon the inner face of the saddle back wall 6 directly beneath the top wall 5 is a fibre plate 10 formed centrally with a circular opening 11 rounded at its edge and being of a diameter greater than that of the spindle A, which spindle engages through said opening when the saddle is disposed thereon. The right angular portion of the saddle back wall 6 is formed at its opposite edges with struck out tongues 6'-6", Figures 1, 4 and 6 that are to be bent over the vertical edges of said fibre plate 10 to secure the same upon said right angular portion of the back wall, see Figure 4.

Secured to the diagonally extending portion of the back wall of the saddle adjacent the lower end thereof is a forwardly extending direct right angular bobbin supporting pin 12 upon which is to be disposed a thread delivery bobbin B. The angularity of the major portion of the saddle back wall is such that when the bobbin is disposed on the pin 12 and the saddle hung upon the spindle, the center of gravity will be directly through the center of the fibre plate 8 so that this plate will have the greatest contact with the spindle. However, insomuch as the saddle will have a tendency to wobble upon the spindle until the same reaches a high rate of speed, the rearmost fibre plate 10 will engage said spindle and consequently limit the wobbling movement of the saddle. It has however been established by actual practice of the invention that after the spindle reaches a rate of speed in excess of five thousand R. P. M. the wobbling action will cease and the saddle and bobbin be supported to a large extent by the fibre washer 8 for consequently lessening the degree of friction between the saddle and the spindle.

As disclosed in Figure 2 of the drawings, it is apparent that in order to permit of the removal or replacement of the saddle with

respect to the spindle it is necessary that the saddle be canted, as per the dotted lines in said Figure 2 after which the saddle may be slid upon or removed from the spindle. In the attachment action, the saddle is held in canted position and then moved inwardly upon the spindle. As soon as the notch 9 of the fibre plate 8 is above the circumferential channel α of the spindle A the saddle is dropped so that the notch 9 of the fibre plate 8 will engage within said channel of the spindle. The saddle will then be locked upon the spindle and be prevented from accidental displacement with respect to the spindle by reason thereof.

In order to permit the spindle A to be grasped by the thumb and forefinger of the operator, the side edges of the saddle top wall 5 are of concave formation as clearly disclosed in Figure 3, the center of the concavities of the edges being spaced a distance substantially equivalent to the diameter of the spindle.

Secured to the top wall 5 of the saddle at one end is a forwardly projecting and slightly curved thread guide wire 13, the outer end of which is provided with a pig tail 14 positioned directly in front of and above the thread intake end of the spindle A and slightly thereabove as indicated in Figures 1 and 3. The thread from the delivery bobbin is passed through the pig tail 14, and thence into the inlet end of the spindle for the purpose of properly guiding the thread into the spindle without any liability of the thread engaging the spindle or any structural element of the saddle per se.

The saddle attached end of the thread guide wire 13 is preferably passed laterally across the top wall of the saddle, and is provided at the edge of the top wall with a spring loop 15, Figure 4, after which the wire is extended downwardly as at 17 adjacent the rear end of the delivery bobbin B, the extreme lower end of this wire being provided with a curved finger 18 for engaging the adjacent flange of the thread delivery bobbin, Figures 1 and 4, for checking the speed of the same during the spinning and twisting operation of the unit.

In the modified form of the invention disclosed in Figure 9, the construction of the saddle is substantially identical with that disclosed in the other figures with the exception that the back wall of the saddle is formed with a pair of outwardly converging branches 6'-6". Upon the lower ends of the branches are delivery bobbin supporting pins 12'-12" for the purpose of supporting a pair of thread delivery bobbins B'-B". In this instance two depending brake wires 17'-17" are provided for engaging the inner flanges of the two delivery bobbins for the purpose previously described.

It will thus be seen that I have provided highly, simple, and efficient forms of saddle construction each of which is well adapted for all the purposes heretofore designated, 5 and even though I have herein shown and described the two forms of saddles disclosed as consisting of certain detail structural elements it is nevertheless to be understood that some changes may be made therein without 10 affecting the spirit and scope of the appended claims.

Having thus described the invention, what I claim as new and desire to secure by Letters Patent is:

15. 1. In a spinning and twisting unit, a rotatable spindle substantially horizontally arranged, and a bobbin supporting structure including a single bearing to carry the major portion of the weight of said bobbin supporting structure suspended from the spindle when the spindle is rotated at a high rate of speed.

20. 2. In a spinning and twisting unit, a rotatable spindle substantially horizontally arranged and a bobbin supporting structure including a single bearing to carry the major portion of the weight of said bobbin supporting structure suspended from the spindle when the spindle is rotated at a high 30 rate of speed, and means for steadyng the bobbin supporting structure in relation to the spindle.

25. 3. In a spinning and twisting unit, a rotatable spindle substantially horizontally arranged having an annular groove, and a bobbin supporting structure including a single bearing to carry the major portion of the weight of said bobbin supporting structure suspended from the spindle, when the 35 spindle is rotated at a high rate of speed, said bearing being of a size to fit the groove but too small to fit the remaining portions of the spindle, thereby preventing longitudinal movement of the structure of the 40 spindle.

45. 4. In a spinning and twisting unit, a rotatable spindle substantially horizontally arranged and having an annular groove, and a bobbin supporting structure including a single bearing to carry the major portion of the weight of said bobbin supporting structure suspended from the spindle when the spindle is rotated at a high rate of speed, said bearing being of a size to fit the groove but too small to fit the remaining portions 50 of the shaft and thereby preventing longitudinal movement of the bobbin supporting structure of the spindle, and means for steadyng the bobbin supporting structure as 55 to the spindle.

60. 5. In a spinning and twisting unit, a rotatable spindle substantially horizontally arranged and a bobbin supporting structure including a single bearing to carry the major portion of the weight of said bobbin sup-

porting structure suspended from the spindle when the spindle is rotated at a high rate of speed, and an annulus circumjacent the spindle and larger in diameter than the adjacent portion of the spindle for steadyng the bobbin supporting structure in relation to the spindle. 70

6. In a spinning and twisting unit, a rotatable spindle substantially horizontally arranged, and a bobbin supporting structure 75 including a single bearing to carry the major portion of the weight of said bobbin supporting structure suspended from the spindle when the spindle is rotated at a high rate of speed, and an annulus on the bobbin supporting structure in spaced relation to the bearing and circumjacent the spindle, said annulus being larger in diameter than the adjacent portion of the spindle. 80

7. In a spinning and twisting unit, a rotatable spindle substantially horizontally arranged and having an annular groove, and a bobbin supporting structure including a bearing engageable with the groove to suspend the bobbin supporting structure under 90 working conditions practically from a single point of the spindle, and an annulus circumjacent the spindle and sufficiently large so as to allow the raising of the bearing from engagement with the groove of the spindle. 95

8. In a spinning and twisting unit, a rotatable spindle substantially horizontally arranged, and a bobbin supporting structure including a single bearing on the supporting structure and forming a part of the bobbin 100 supporting structure and being open at its bottom so that it may be lifted from the spindle.

9. In a spinning and twisting unit, a rotatable spindle substantially horizontally arranged, and a bobbin supporting structure including a single bearing on the supporting structure and to suspend the supporting structure from the spindle under working conditions, said bearing being open at its 105 bottom so as to allow it to be lifted from the spindle, and means preventing longitudinal movement of the bearing on the spindle, said bearing being further capable of being freed from said means when lifted 110 from the spindle.

10. In a spinning and twisting unit, a rotatable spindle substantially horizontally arranged, and a bobbin supporting structure including a single bearing on the supporting 120 structure and to suspend the structure from the spindle under working conditions, means for preventing longitudinal movement of the bearing on the spindle, said bearing being open at its bottom so as to allow it to be lifted from the spindle and said means, and an annulus on the supporting structure circumjacent the spindle and being larger in diameter than the adjacent portion of the spindle, so as to allow the lifting of the bear- 125 130

ing from the spindle and from said means.

11. In a spinning and twisting unit, a rotatable spindle substantially horizontally arranged, a bobbin supporting structure to suspend the bobbins from the spindle, and a member associated with the supporting structure for frictionally engaging the bobbins for checking the rotation thereof.

12. In a spinning and twisting unit, a rotatable spindle substantially horizontally arranged, a bobbin supporting structure to suspend the bobbins from the spindle, and a thread guide member associated with the supporting structure and projecting forwardly thereof to a point at the end of the spindle and a thread guide at the spindle end of the member.

13. In combination, a rotatable spindle substantially horizontally arranged, and bobbin supporting means including a bearing on the spindle to suspend said bobbin supporting means from the spindle, said bearing substantially coincident with the center of gravity of the bobbin supporting means.

14. In combination, a rotatable spindle substantially horizontally arranged, and bobbin supporting means including an inner apertured portion loosely receiving the spindle and also including an outer bearing on the spindle to suspend said bobbin supporting means from the spindle under working conditions, said bearing substantially coincident with the center of gravity of the bobbin supporting means.

15. In combination, a rotatable spindle substantially horizontally arranged, and bobbin supporting means including an inner apertured portion loosely receiving the spindle and an outer bearing on the spindle to suspend said bobbin supporting means from the spindle under working conditions, said bearing substantially coincident with the center of gravity of the bobbin supporting means, and a member associated with the bobbin supporting means and arranged to

frictionally engage a bobbin to check the rotation thereof.

16. In combination, a rotatable spindle substantially horizontally arranged and having a circumferential groove, and bobbin supporting means including an inner portion and an outer portion and also including an apertured plate in the inner portion and receiving a spindle and a bifurcated plate in the outer portion and arranged to straddle the grooved portion of the spindle, said outer plate constituting a bearing on the spindle to suspend said bobbin supporting means from the spindle under working conditions, and said outer plate being arranged substantially coincident with the center of gravity of the bobbin supporting means.

17. In combination, a rotatable spindle substantially horizontally arranged, and bobbin supporting means including an outer bearing on the spindle to suspend the bobbin supporting means from the spindle, said outer bearing substantially coincident with the center of gravity of the bobbin supporting means, and also including an inner apertured portion loosely receiving the spindle and a portion pendent from said inner portion and having a bobbin carrying pin inclined from the horizontal.

18. In combination, a rotatable spindle substantially horizontally arranged, and bobbin supporting means including an outer bearing on the spindle to suspend the bobbin supporting means from the spindle, said outer bearing substantially coincident with the center of gravity of the bobbin supporting means, and also including an inner apertured portion loosely receiving the spindle and a portion pendent from said inner portion and having a bobbin carrying pin inclined from the horizontal, and further having a member for frictionally engaging a bobbin on said pin.

In testimony whereof I affix my signature.

FRED C. WERBER.
